COMBINED PEN AND WRIST BAND HOLDER THEREFOR

Anthony Laudani, Franklin Square, N. Y.

Application July 29, 1954, Serial No. 31,651

Term of patent 7 years

(Cl. D74—17)

To all whom it may concern:

Be it known that I, Anthony Laudani, residing at Franklin Square, Nassau County, New York, have invented a new, original, and ornamental Design for a Combined Pen and Wrist Band Holder Therefor, of which the following is a specification, reference being had to the accompanying drawings, forming a part hereof.

Fig. 1 is a top plan view of a combined pen and wrist band holder therefor showing my new design with parts of the wrist band being shown broken away for convenience of illustration;

Fig. 2 is a bottom plan view;

Fig. 3 is a side elevational view;

Fig. 4 is another top plan view thereof as it appears with the pen disengaged from the holder;

Fig. 5 is a sectional view thereof taken on the line 5—5 of Fig. 4; and

Fig. 6 is a plan view of the pen as it appears in extended position.

I claim:

The ornamental design for a combined pen and wrist band holder therefor, as shown.
